GASOLINE TYPE FUEL COMPOSITION

Victor F. Massa, Union, N. J., and Barrett B. Russell 3rd, Park Forest, Ill., assignors to Esso Research and Engineering Company, a corporation of Delaware

No Drawing. Application October 4, 1951,
Serial No. 249,818

6 Claims. (Cl. 44—69)

This invention concerns a novel process for minimizing formation of combustion deposits in an internal combustion engine. The process of this invention may be embodied in novel fuel compositions operative when burned in an internal combustion engine to aid in the removal of deposits from the engines. These compositions are characterized by inclusion of aluminum alcoholate in gasoline type fuels resulting in the deposition of aluminum compounds in the combustion chamber of an engine. These aluminum compounds are characterized by a substantially different coefficient of expansion than those deposits ordinarily accumulating in an engine. As a result, by securing the deposition of these aluminum compounds intermixed with conventional deposits having substantially different coefficients of expansion, flaking of the total deposit from the engine will be achieved during variations in the temperature of the engine.

It is generally recognized in the automotive and fuel industries that a need exists for a method of minimizing or removing engine deposits from internal combustion engines. This is particularly apparent in connection with automotive engines where it is now known that engine deposits account for a substantial increase in the octane requirements of an engine after prolonged use. It has been found that due to combustion chamber deposits, it is necessary to increase the octane rating of fuel supplied to an engine by as much as 5 to 25 octane numbers in order to prevent knocking of the engine.

By analysis of the deposits, it has been found that the engine deposits which result in an internal combustion engine burning a gasoline fuel are predominantly carbonaceous on a volume basis. A portion of the troublesome engine deposits is made up of lead salts present in the form of several different types of lead compounds resulting from tetra-ethyl lead included in the fuel as an anti-detonant. While these lead deposits are relatively heavy and make up a substantial portion of the deposit by weight, lead deposits in fact account for a small proportion of the total volume of engine deposits.

It has now been conceived that by intentionally causing deposition of a material having a substantially different coefficient of expansion, the admixture of this material with carbonaceous and lead deposits in the engine will cause fracture of the deposits so as to maintain the engine in a relatively clean condition. In accordance with this invention therefore, a metal compound is to be injected into an internal combustion engine so as to secure deposition in the engine of a metal salt or oxide preferably having a high coefficient of expansion, since carbonaceous deposits have a relatively low coefficient of expansion. Intermingling of the deposits of this metal compound with the conventional carbonaceous deposits creates a condition causing the deposits to flake away from the engine during variations in engine temperature. A portion of this effect may be secured during each cycle of engine operation, although there is greater oppor-

2

tunity for scaling of this character to occur during idle periods at which the engine temperature can drop to ambient temperatures. In any case, the flaked deposits are carried from the engine with the exhaust products during successive engine operation.

In order to secure this objective, it is necessary to supply a suitable metal compound to the engine to permit deposit in the engine of a substance having a high coefficient of expansion. To attain this objective it is undesirable to employ stable metal compounds, which for the most part would simply pass through the engine without deposition in the combustion chamber. However, if compounds such as aluminum alcoholates are employed, these compounds will be readily decomposed under the conditions existing in the combustion zone so as to deposit in the engine in the form principally of aluminum oxide. Thus, moisture resulting from the combustion of the fuel will readily hydrolyze the aluminum alcoholate resulting in the deposition of alumina in the combustion chamber.

Aluminum alcoholates having from 3 to 10 carbon atoms may be employed in the practice of this invention. An example of such alcoholates is aluminum isopropoxide which is presently contemplated as being a preferred compound. Due to the relatively low volatility of aluminum alcoholates it is preferred that the lower molecular weight aluminum alcoholates be employed so that the C₃ to C₅ aluminum alcoholates are generally preferable. These compounds are to be employed in a range of about 0.001% to about 0.1% by weight in the fuel compositions of this invention. Employing concentrations of the aluminum compound outside of this range is generally not desired. For continuous operation in an engine, it is generally suitable to employ no more than about 0.01% by weight of the aluminum compounds.

Solution of the selected aluminum alcoholate in a fuel composition may be aided by a suitable agent to keep the aluminum compound in suspension or to solubilize the aluminum alcoholate. Peptizing agents are generally operative to provide this function. Examples of such compounds are sodium petroleum sulfonate and an alkali metal or alkaline earth metal alkyl phenol sulfide or disulfide such as barium diisobutyl phenol sulfide, employed alone or in combination. Inclusion of about 0.001% to about 0.01% of these compounds by weight is generally satisfactory to solubilize the aluminum alcoholates.

It is particularly preferred in obtaining the benefits of this invention to include the aluminum alcoholate alone or together with a solutizer, as identified, in an auxiliary fluid to be injected in the engine. Thus, in cases in which an engine has been provided with an auxiliary fuel tank and injector system, it is valuable to practice the present invention by injecting the aluminum alcoholate through this system. In this case it is particularly desirable to dissolve the aluminum alcoholate in an alcohol which may then be injected into the engine according to the conventional practice.

In the case in which the aluminum alcoholate is included as a constituent in conventional gasoline type fuels any desired type of fuel base may be employed. Thus the fuel base may be defined as a mixture of hydrocarbons boiling in the gasoline boiling range derived from refining of petroleum oil or from suitable hydrocarbon synthesis processes. The gasoline base may be a virgin, catalytically cracked, thermally cracked or hydroformed gasoline, or any of the other conventional gasoline bases. In addition to the aluminum alcoholate and a solutizer for the aluminum alcoholate, if desired, conventional gasoline additives may be employed. Thus, a lead alkyl anti-detonant, lead scavenging agents, dyes, anti-oxidants, solvent oils, etc. may also be included in the compositions,

As indicated therefore, the present invention concerns a method for minimizing adherence of engine deposit formations. According to this method, engine deposits may be substantially reduced by injection of a minor portion of aluminum alcoholate, having from 3 to 10 carbon atoms into the engine. The aluminum alcoholate may be introduced in a separate injection system or may be introduced in admixture with any desired type of gasoline. In either case the aluminum alcoholate decomposes in the combustion zone to form aluminum oxide which deposits on those portions of the engine on which carbonaceous and lead deposits ordinarily form. The aluminum oxide, having a substantially different coefficient of expansion from the other constituents of the engine deposit admixed therewith, creates a flaking effect particularly when the engine has had an opportunity to cool off during shut-down after periods of engine operation. Thereafter on subsequent operation of the engine these deposits are for the most part blown from the engine through the exhaust system. It is apparent that fuels containing alcoholates may be used continuously in an engine to minimize deposits in this manner, or alternatively intermittent operation utilizing the fuel compositions of this invention may be carried out.

What is claimed is:

1. An improved gasoline composition containing a lead alkyl anti-detonant and 0.001 to 0.1% of an aluminum alcoholate having from 3 to 10 carbon atoms.

2. The composition of claim 1 having from 3 to 5 carbon atoms.
3. The composition defined by claim 1 in which the said aluminum alcoholate constitutes aluminum isopropoxide.
4. The composition defined by claim 1 including about 0.001% to 0.01% of a peptizing agent adapted to solubilize the said aluminum alcoholate.
5. The composition defined by claim 4 in which the said peptizing agent constitutes sodium petroleum sulfonate.
6. The composition defined by claim 4 in which the said peptizing agent constitutes an alkali metal alkyl phenol sulfide.
